UNITED STATES PATENT OFFICE.

ALEXANDER P. MENDE, OF NEW YORK, N. Y.

DRYING APPARATUS.

SPECIFICATION forming part of Letters Patent No. 664,962, dated January 1, 1901.

Application filed October 15, 1900. Serial No. 33,080. (No model.)

To all whom it may concern:

Be it known that I, ALEXANDER P. MENDE, a citizen of the United States, and a resident of New York city, county and State of New York, 5 have invented certain new and useful Improvements in Drying Apparatus, of which the following is a specification.

This invention relates to a drying apparatus of improved construction, and more particularly to the means for conveying the steam or other heating medium to the shelves that support the material to be dried.

By my invention all exterior steam connections are avoided, leakage is prevented, and 15 a structure of superior strength is obtained.

The invention consists in the various features of construction fully pointed out in the claims.

In the accompanying drawings, Figure 1 is 20 a vertical transverse section of my improved drying apparatus on line 1 1, Fig. 2; Fig. 2, a horizontal section on line 2 2, Fig. 1, with the shelves partly broken away; and Fig. 3, a vertical longitudinal section on line 3 3, Fig. 25 1, partly in elevation.

The letter *a* represents a shell or casing of rectangular or other form and open, preferably, at both ends. These ends are closed by the doors *a'*, each hung, preferably, on a double hinge, so that it will approach its seat squarely. To this effect the door is provided near its center with lugs *a²*, carrying a pintle *a³*, that is surrounded by the inner end of a link *a⁴*. The outer end of this link is pivoted 35 at *a⁵* to the casing *a*. When the door is opened or closed, the link *a⁴* will turn on the outer pintle *a⁵*, while the door will turn on the inner pintle *a³* and will thus be centrally supported. Swinging bolts *a⁶* serve to lock 40 the door when closed against its seat.

Within the casing *a* are secured a series of brackets or rails *b*, adapted to support a series of hollow drying-shelves *c*, arranged above one another and each composed, preferably, 45 of a front and of a rear section, Fig. 2. Each of the shelves may be reinforced by a number of interior props *c'* and by a wrought-iron end plate *c²*, as shown.

In order to supply the steam or other heat-

ing medium to the shelves, I cast bodily within 50 the wall of the casing *a* the steam inlet and exit headers or ducts *d e*, one preferably at each corner, Fig. 2. These ducts are provided at their inner side with a series of perforations adapted to receive branch pipes *g h*, 55 which are removably connected within the casing by couplings *g² h²* to corresponding branch pipes *g' h'*, entering the shelves *c*. The steam entering the inlet-ducts *d* passes simultaneously through the branches *g g'* into 60 all of the shelves *c* and is then discharged through the branches *h h'* into the exit-ducts *e*. Thus it will be seen that all of the shelves are heated uniformly and that as the headers and connections are all arranged within the interior 65 of the casing leakage is prevented.

In order to exhaust the air and also the gases and vapors emanating from the material under treatment, I provide the apparatus with an exhaust-pipe *i*, communicating with 70 the air-pump *i'*. An automatic vacuum-regulating valve *j* permits the degree of air rarefaction to be accurately controlled, this valve being more particularly described in another application for a patent filed by me on even 75 date herewith under serial number 33,079 and to which reference is hereby made.

The temperature of the drier is regulated by a thermostat, which controls the steam-inlet valves *l* and of which the pipe *l'*, that contains the expansive medium, is illustrated. This thermostat is also more fully shown in the patent application hereinabove referred to.

The advantages of my improved drier are that in it all the exterior couplings and steam 85 connections are entirely avoided and that increased strength is obtained, while leakage is prevented.

What I claim is—

1. In a drying apparatus, a casing provided 90 with a perforated steam-inlet header and a perforated steam-outlet header formed bodily by the wall of the casing, combined with drying-shelves, and branch pipes that connect the headers to said shelves, substantially as 95 specified.

2. In a drying apparatus, a casing provided with a perforated steam-inlet header and a

perforated steam-outlet header formed bodily by the wall of the casing, combined with dry-
ing-shelves, branch pipes connected to the
headers and shelves respectively, and coup-
lings that connect said branch pipes to one
another within the casing, substantially as
specified.

Signed by me at New York city, county and
State of New York, this 12th day of October,
1900.

ALEXANDER P. MENDE.
